D10-1.

OR D 7,768

EX

UNITED STATES PATENT OFFICE.

FLORENCE KROEBER, OF HOBOKEN, NEW JERSEY.

DESIGN FOR CLOCK-CASES.

Specification forming part of Design No. 7,768, dated September 22, 1874; application filed August 15, 1874.
[Term of Patent 3½ years.]

CASE C.

To all whom it may concern:

Be it known that I, FLORENCE KROEBER, of Hoboken, in the county of Hudson and State of New Jersey, have invented a new and original Design for a Clock, of which the following is a specification:

The accompanying engraving represents a face view of my new design for a clock.

This invention relates to the new configuration of the case of a pendulum-clock, and to a new ornamentation thereof.

The base of the case is in three parts, the end parts *a a* being in form of cubes, while the middle part *b* is a narrower band, ornamented in the center by a rosette, *c*. The sides of the case are straight up and down, but from them project outwardly-inclined braces *d d*, which terminate at their upper ends in rosettes *e e*, and at their lower ends in volutes *f f*, as shown. It will be observed that the rosettes *e e* are much farther apart than the volutes *f f*, which gives (together with the triangular open spaces *g g*, which are left between

the sides of the case and the braces *d*) quite a peculiar effect to the structure. The top of the case is or may be ornamented by a crowning rosette, *h*, which is flanked by leaves *i i*, while the rosettes *e e* are the bearers of ornamental leaves *j j*. Pendent leaves *k k* are applied to the volutes *f f*, and quarter rosettes *l l* are placed in the corners formed by the sides of the frame and the base as shown.

I claim as my invention—

1. The design for the base of a clock-case, consisting of the parts *a b a*, as shown.
2. The design for the configuration of the clock, consisting of the outwardly-projecting braces *d d* and rosettes *e e*, said braces forming the open spaces *g g*, as shown.
3. The design for the ornamentation of the clock-case by the parts *h i j k*, and *l*, as shown.

F. KROEBER.
